SOLE STRAIGHTENING DEVICE FOR SHOES

Norman C. Dahl, Boston, Mass., assignor to Dex-dahl, Inc., Cohasset, Mass., a corporation of Massachusetts

Application September 8, 1950, Serial No. 183,785

9 Claims. (Cl. 12—129.1)

1

The present invention relates to boot holders for holding ski boots and other types of thick-soled shoes when not in use.

It is well recognized that the regular use of shoe trees in leather shoes serves to preserve the shoes in proper shape. For most shoes, the common interval shoe tree serves both to support the upper against wrinkling and to hold the sole in reasonably straight condition.

In the case of ski boots and other types of thick-soled shoes, however, the soles are so stiff that it becomes impractical to employ an internal, longitudinally extensible type of tree because of the hazard of damage to the upper of sufficient force is applied to maintain the sole in properly straightened condition. Furthermore, it is difficult with an internal tree to provide proper ventilation in order that all parts of a wet boot may dry evenly.

It is, therefore, an object of the invention to provide a boot tree of the external type, constructed and arranged to hold a pair of thick-soled boots such as ski boots, with the soles positively secured against twisting or curling, and without longitudinal compression on the boot sole.

It is likewise an object of the invention to provide a boot tree wherein the boots may readily be inserted and clamping pressure thereafter applied in quick and easy fashion. More specifically, the invention contemplates boot holding means wherein the clamping devices are arranged to swing out of the way when a boot is to be inserted, and to be returned to and locked in boot-engaging position during the application of clamping pressure.

In the drawings illustrating the invention, Fig. 1 is a plan view of my invention according to the preferred embodiment thereof; Fig. 2 is a view in side elevation, partly in section and showing a boot clamped on one side of the device; Fig. 3 is a detail view of one of the heel clamping mechanisms, looking toward the rear; Fig. 4 is a detail side view, partly in section and taken on the line 4—4 of Fig. 3, showing the heel clamping mechanisms, one in locked position and the other released for rearward swinging movement; Fig. 5 is a side view showing the device with a pair of boots clamped therein; Fig. 6 is a view of a modification of the construction illustrated in Figs. 3 and 4; Figs. 7 and 8 are views in plan and side elevation, respectively, showing an alternative form of device; Fig. 9 is a plan view and Fig. 10 is a view in side elevation of a modification of the structure shown in Figs. 1 to 4, embodying unitary clamping means; Fig. 11 is a detailed

2

plan view of the pivotally mounted heel clamp member thereof, shown in locked position, and Fig. 12 is a detailed view partly in section, showing the clamp unlocked and tilted to permit insertion of a boot in the holder.

The device illustrated in Figs. 1—5 employs separate base members 12 and 14. The front member 12 supports the forward part of the shoe and carries the toe clamping means, while the rear member 14 carries the heel securing devices. These base members 12 and 14 may conveniently be formed of wood or other suitable material, and preferably are grooved on both faces to allow free access of air to the underside of the boot sole. To permit adjustment of the device for boots of different lengths, the base members are slideable toward and from one another within U-shaped metal side channels 16 when the wing nut 18 of clamp bolt 20 is loosened. Once the proper spacing has been obtained for a particular pair of boots, no further adjustment is necessary, and the boots may be removed and replaced without moving the base members relative to one another.

25 The device is arranged to provide on each side thereof positive clamping means for independently securing a ski-boot with the sole held in properly flattened condition. To this end, the boots are engaged at their extreme ends by means that exert downward pressure only, so as to permit maximum straightening action without longitudinal compression. Thus, the toes of the boots are held by the tip of the sole beyond the upper, to secure maximum leverage and to insure that the entire shoe will be held in proper shape.

30 The toe clamps 28 are advantageously formed of metal, having their ends shaped to a box section to prevent rocking relative to the studs 30 when clamping pressure is applied by wing nuts 32. Light coil springs 34 beneath the toe clamps conveniently maintain the clamps lifted against the wing nuts to receive the toe of the boot. Preferably the sole-engaging central portion 36 of the clamps 28 is curved in an arc to permit the clamp to engage and fit over substantially the entire forwardly extending margin of the sole beyond the upper.

35 The heel clamps indicated generally at 40 are arranged to apply positive downward clamping pressure to the heel of the boot so that the boot may be locked in straightened position without involving any longitudinal compressive force on the sole. Like the toe clamps, the heel clamps are independently mounted and actuated, so that

only one boot at a time need be inserted and clamped.

Each heel clamp comprises a sole-engaging member 42 having its clamping face curved in an arc to fit around the heel portion of the boot and thereby permit distribution of the clamping pressure. The member 42 is moved into clamping position by toggle mechanism comprising a pair of links 44 connected to the arms of a hand lever 46 which in turn is pivotally mounted on the uprights 48 of the heel clamp support. The uprights are slotted to permit heightwise adjustment of the pivot screws 50 for the hand lever, in order that the spacing of the clamp member 42 from the base, when the toggle is closed, may be adjusted to suit the thickness of the boot heel. To insure that the clamping member 42 may be guided in proper position, it is provided with projecting lugs or ears 52 which slide within the slotted uprights 48. Transverse serrations 54 on the inner faces of the uprights 48 and on the clamping washers 56 to serve to prevent the toggle mechanism from slipping upwards when the boot is clamped.

The heel clamps 40 are mounted on the rear base member 14 for limited rearward swinging movement, to facilitate insertion of the boot. However, provision is made for automatically locking the clamps in upright position during clamping. The mounting of the clamps is best shown in Figs. 3 and 4, wherein it will be apparent that the lower ends of the uprights 48 are received within slots 57 in the base 14 adjacent the side edges. Pins 58 extend laterally through the slotted uprights to retain the uprights within the slots, while permitting sliding and limited tilting movements.

In order that the heel clamps may be operated independently of one another, they are offset longitudinally of the base, with separate retaining pins 58, as particularly shown in Fig. 4. The toe clamping members 28 are therefore mounted in correspondingly offset relation, in order that the separation between heel and toe clamps on the two sides of the device may be alike.

The locking of the heel clamps in upright position is effected through the provision of transverse slots 60 formed in the base 14 on each face thereof. As shown in Fig. 4, when the uprights 48 are substantially perpendicular to the base 14, the cross-member 62 joining the lower ends of the uprights 48 may be drawn into the slot. Such engagement, in conjunction with the pins 58 within the slots in the uprights, serves to lock the heel clamp assembly against rearward tilting displacement, so that the toggle clamp may be actuated without risk of the heel-engaging member 42 slipping from its seat on the top surface of the boot heel, or from the groove in the heel, in the event the boot presents no break at the junction of heel and upper to receive the member 42. On the other hand, by sliding the uprights through the base far enough to release the cross-member 62 from its slot 60, the whole heel clamp assembly may readily be tilted away from the boot in the manner illustrated in Fig. 4, so as to permit removal or replacement of the boot without requiring adjustment of the spacing between toe and heel clamps.

It will be apparent that the device permits a pair of ski boots quickly to be inserted and firmly clamped, without in any way marring the soles or uppers. In utilizing the device, one boot at a time will be inserted, first the toe under the toe clamp and the thumb screws thereof

turned down. If any lengthwise adjustment is needed, this may be effected by loosening the thumb screw 18 and moving the bases 12 and 14 toward or from one another, as the case may be.

The heel clamp assembly is then brought to upright position and locked therein by lifting the assembly away from the base to seat the bar 62 in slot 60. The hand lever 46 may then 10 be moved downwardly to extend the toggle and bring the heel engaging member 42 onto the top edge of the boot heel. Further movement of the hand lever will then carry the heel down into contact with the base, while the toggle arms move past their center line to locked position. If adjustment is needed, the thumb screws 5 may be loosened and the pivot screws 50 raised or lowered in the uprights until the desired pressure is obtained when the toggle is moved to 20 clamped position. After initial adjustment of the toe clamp, length, and heel clamp toggle position, only the heel clamp hand lever 46 need be actuated to remove or insert the boot.

In similar fashion, the other boot may be 25 clamped in place on the other side of the device, without interfering with the clamps of the first boot. The device with boots in place may then be hung in a convenient location or readily carried by strap 66, with assurance that the boots 30 will be held straight with the entire toe portion of the sole properly flattened, yet without any longitudinal compression thereon, and with no interference with proper drying.

In lieu of the pins 58 which pass transversely 35 through the edge portions of the base 14 to retain the heel clamp uprights 48, the arrangement shown in Fig. 6 may be employed. Here the heel clamps are retained by means of plates 40 70 having tongues 72 which extend into the slots in the uprights 48. The plates are mounted by screws 74 on both sides of the rear base member 14, each plate being mounted directly opposite, a locking slot 60 for the crossbar 62 of each clamp, so that the clamps may automatically lock 45 in vertical position when cross-bars are seated within their respective slots, as previously described.

An alternative construction is illustrated in 50 Figs. 7 and 8, wherein a single base member 80 is employed. While only a single set of toe and heel clamps is shown, similar clamps may be mounted on the other ends of the studs on the opposite side of the base. For longitudinal adjustment, the toe clamp 82 may be slotted at 55 84 to permit varying its position on the stud 86 beneath wing nut 88, while a series of holes 89 permit placing the stud in various positions along the base to accommodate a wide range of shoe sizes.

The heel clamping member 90 is mounted on 60 studs 92 provided with wing nuts 94. The member is arranged for rearward swinging movement, as in the first described embodiment, to facilitate insertion of the boot. For this purpose the member is slotted at one end at 96, so that such end may be disengaged from the stud. An angle member 100 is carried by the stud and, when swung in back of the clamp 90, prevents the latter from moving rearwardly as the thumb screws are tightened. On the other hand, the angle member 100 may readily be swung to the side, to the position shown in dotted line in Fig. 7, to allow the clamp to be 65 opened for insertion or removal of the boot. As 70 75 has already been indicated, similar toe and heel

clamps may be mounted on the other ends of the studs 86 and 92, so that a pair of boots may be mounted, as in the first described embodiment, one on each side of the base board, but entirely independent in respect to operation of the clamping instrumentalities.

The advantages of the arrangement shown in Figs. 1-4 are substantially retained in the modification shown in Figs. 9-12, wherein a single toggle clamping mechanism serves for both boots. Like the first-described embodiment, front and rear base members 104 and 106 are adjustably secured in side channels 108. Toe clamps 110 are mounted on opposite sides of the base, in aligned instead of offset relation.

The heel clamping means comprises a pair of slotted uprights 112 which extend through and project on both sides of the heel base 106. Transverse pins 114 (or a tongued plate such as shown in Fig. 6) retain the uprights in place while permitting sliding and tilting movement relative to the base.

On one side of the base, the uprights carry a sliding heel clamp 116 and toggle mechanism comprising handle 118 and connecting links 120, as in the first-described embodiment. On the other side of the base, the uprights are connected to another heel clamp 124 for engaging the boot on that side of the base. For ease in inserting and removing the boot, the clamp 124 is pivoted on the uprights, so as to swing rearwardly, as shown in the detail view, Fig. 12, yet can be locked in clamping position when boots are to be clamped.

To this end, the clamp 124 is provided with short arms 126 which are connected to the uprights by rivets 128 extending through the slots, thereby permitting sliding as well as tilting movement of the clamp relative to the uprights 112. The outer ends of the uprights are bent inwardly at 130, so as to overlie the ends of the clamp when the latter is tilted to clamping position (see Fig. 11). Rearward movement of the clamp is prevented, under these conditions, by lugs 132 which project upwardly from the clamp in front of the extensions 130.

To release the clamp 124 and permit it to swing rearwardly out of the way of the boot, the toggle mechanism is first unlocked to release the clamping pressure. The clamp is then moved inwardly off the uprights until the lugs 132 clear the extensions 130, after which the clamp will freely swing out of the way, as shown in Fig. 12. The reverse procedure is equally simple, when boots are to be inserted and clamped. The clearance provided by swinging clamp 124 out of the way permits ample rearward tilting movement of the uprights and toggle assembly on the other side of the base to carry the other heel clamp 116 out of the way of the boot on that side. If desired, the outer ends of the uprights 112 may be joined by a cross bar 136 to hold the uprights in parallel relation.

I have thus described preferred and alternative constructions of boot tree, particularly advantageous for ski boots but useful for other types of thick soled boots wherein the insertion and removal of the boots may readily be carried out, and wherein extremely powerful clamping means are provided to insure that the soles will positively be held in properly straightened condition without stretching or distorting the upper.

I claim as my invention:

1. A boot holder for supporting a thick-soled boot with the sole in flattened condition com-

prising supporting means against which the sole of the boot is clamped, toe clamping means for securing the forepart of the sole to the support, and heel clamping means comprising a heel-engaging member movable toward and from the support, a pair of arms having guideways within which the heel engaging member is movable, and toggle means for applying clamping pressure to the heel-engaging member.

10 2. A boot holder for supporting a thick-soled boot with the sole in flattened condition comprising supporting means against which the sole of the boot is clamped, toe clamping means for securing the forepart of the sole to the support, and heel clamping means comprising a heel-engaging member movable toward and from the support, a pair of arms having guideways within which the heel engaging member is movable, and toggle means for applying clamping pressure to the heel-engaging member, said means comprising a toggle lever pivotally connected to the arms, and a pair of links connecting the toggle lever to the heel-engaging member.

20 3. A boot holder for supporting a thick-soled boot with the sole in flattened condition comprising supporting means against which the sole of the boot is clamped, toe clamping means for securing the forepart of the sole to the support, and heel clamping means comprising a heel-engaging member movable toward and from the support, a pair of arms having guideways within which the heel engaging member is movable, and toggle means for applying clamping pressure to the heel engaging member, said means comprising a toggle lever pivotally connected to the arms, and a pair of links connecting the toggle lever to the heel-engaging member, the position of the pivotal connection of the toggle lever to the arms being adjustable to vary the height of the heel engaging member from the support when the toggle lever is in clamping position.

30 4. A boot holder for supporting a thick-soled boot with the sole in flattened condition comprising supporting means against which the sole of the boot is clamped, toe clamping means for securing the forepart of the sole to the support, and heel clamping means comprising a heel-engaging member movable toward and from the support, a pair of arms having guideways within which the heel engaging member is movable, means for applying clamping pressure to the heel-engaging member, means connecting the arms to the support for rearward swinging movement, and means for locking the arms in a position substantially normal to the support.

40 5. A boot holder for supporting a thick-soled boot with the sole in flattened condition comprising supporting means against which the sole of the boot is clamped, toe clamping means for securing the forepart of the sole to the support, and heel clamping means comprising a heel-engaging member movable toward and from the support, a pair of arms having guideways within which the heel engaging member is movable, means for applying clamping pressure to the heel-engaging member, means connecting the arms to the support for rearward swinging movement, said arms being joined by a cross-member disposed on the opposite side of the support from the heel-engaging members carried by said arms, the support being grooved to receive the cross-member for locking the arms in a position substantially normal to the support.

75 6. A boot holder for supporting a thick-soled

boot with the sole in flattened condition comprising supporting means against which the sole of the boot is clamped, toe clamping means for securing the forepart of the sole to the support, and heel clamping means comprising a heel-engaging member movable toward and from the support, a pair of arms having guideways within which the heel engaging member is movable, means for applying clamping pressure to the heel-engaging member, means pivotally connecting the arms to the support for rearward swinging movement, the arms in the vicinity of the pivot being slotted to permit sliding movement of the arms relative to the support, and means for locking the arms against rearward swinging movement when the arms are drawn upwardly of the support.

7. A boot holder for supporting a thick-soled boot with the sole in flattened condition comprising a front base member, toe clamping means carried thereby having a sole-engaging member shaped to fit over the margin of the sole beyond the toe, a rear base member, heel clamping means carried thereby having a heel-engaging member shaped to fit around and engage the rear portion of the heel, the front and rear base members being mounted in channel members engaging the sides of the front and rear members for longitudinal adjustment of the separation between toe and heel-engaging members, the heel clamping means including an upright, and toggle means for urging the heel-engaging member downwardly relative to the upright to clamp the heel of the boot to the support.

8. A boot holder for supporting a pair of thick-soled boots on opposite sides of a support with the soles in flattened condition, comprising toe clamping means for securing the forepart of each boot to the support, and heel clamping means comprising a pair of uprights extending transversely of the support in the vicinity of the heels of the boots and slidably in said transverse direction relative to the support, a heel engaging

member slidably mounted on the uprights, toggle mechanism for urging said member toward the support, a second heel engaging member carried by the uprights on the other side of the support, a pivotal connection between said heel engaging member and uprights to provide rearward swinging movement of said member and means for locking said member against swinging movement, when clamping pressure is applied thereto.

9. A boot holder for supporting a pair of thick-soled boots with the soles in straightened condition comprising a front supporting member having toe clamping means mounted on opposite sides thereof, a rear supporting member having heel clamping means mounted on opposite sides thereof, two U-shaped channels embracing the longitudinal side margins of the front and rear supporting members to connect said members in longitudinally adjustable relation with the toe and heel clamping means exposed on both sides, and clamping means extending between the channels intermediate the front and rear supporting members for drawing the channels into clamping engagement with the members to retain the latter in adjusted position.
